UNITED STATES PATENT OFFICE

2,465,687

BUILDING CONSTRUCTION

Otto S. Jacobsen, Chicago, Ill.

Application September 23, 1944, Serial No. 555,487

1 Claim. (Cl. 72—29)

1

This invention relates generally to building constructions and more particularly to wall and floor constructions made up of a plurality of pre-cast concrete plates or slabs secured together by spacer members.

Various attempts have heretofore been made to enable floor and wall building structures to be constructed by interlocking a plurality of concrete slabs with spacer members interposed between the slabs. In a number of these prior structures with which I am familiar, certain problems and difficulties have been encountered which the present invention seeks to overcome. For example, it has not been uncommon heretofore, in the erection of floor and wall structures of the type referred to above, to experience considerable breakage during the assembly or interlocking of the constituent parts. In some instances this has resulted from the necessity of inserting tongues on one part into complementary grooves in another part. In pre-casting either plates or spacing members dimensional tolerances cannot be held very close. In other words, considerable latitude must be allowed for variations in sizes of the interlocking parts. As a result, difficulty has been experienced in attempting to insert a tongue of one part into a complementary groove of another part without either obtaining a loose fit or a fit so tight that breakage would ultimately result. The present invention contemplates a simplified slab and spacer construction in which the interlocking of the parts is accomplished in such a way as to preclude breakage which has heretofore been experienced, and also to enable interlocking of these parts with a minimum amount of effort and skill on the part of the workman.

Complications and inconveniences which have heretofore arisen in the assembly of tongue and groove structures have also been obviated by the present invention because the present invention contemplates an arrangement whereby the parts may be interlockingly associated with each other by building one upon the other or one next to the other in a fashion which is as convenient and expeditious as the conventional practice of laying one brick upon or adjacent to another in the building of a wall.

It is a further object of the present invention to provide a building construction as set forth above in which the constituent parts are extremely simple in structure and are capable of being pre-cast of concrete and the like with the utmost economy.

Another object of the present invention is to provide a wall or floor structure as previously identified, which lends itself readily for use with concrete fill poured into the areas between the wall or slab spacers.

The invention further contemplates a slab and

2

spacer construction wherein the spacers may be adjustably positioned along the slabs so as to accommodate openings as they may be required in any portion of the wall or floor, as, for example, to allow for windows, doors, pipes, stairs, skylights, and the like.

Another object of the present invention is to provide, in the wall or floor construction referred to above, slabs which because of the presence of an intermediate strengthening rib, will effectively resist tendencies to crack.

The foregoing and other objects and advantages will be more apparent from the following description, when considered in connection with the accompanying drawings, wherein:

Figure 1 is a perspective view showing a fragmentary portion of two intersecting walls and a floor constructed in accordance with the teachings of the present invention;

Figure 2 is a horizontal sectional view taken along the line 2—2 of Figure 1;

Figure 3 is a vertical sectional view taken substantially along the line 3—3 of Figure 1;

Figure 4 is an enlarged fragmentary perspective view of two pairs of opposed wall plates or slabs and spacing members, the upper slabs of one pair being displaced upwardly to more clearly illustrate the simplified interlocking arrangement contemplated by the present invention;

Figure 5 is a perspective view of a pair of wall plates or slabs and a pair of companion spacer members disassociated from each other to more clearly illustrate the structural details thereof;

Figure 6 is an enlarged perspective view taken from the left of Figure 1 to more clearly illustrate the manner in which the present invention enables the concrete fill to extend completely around the building at the juncture of the floor and wall, and the manner in which this portion of the fill ties in with the vertical fill portions;

Figure 7 is an enlarged perspective view of the lower right hand corner of Figure 1 to illustrate the manner in which the fill extending in the form of beams transversely of the floor ties in with the concrete fill within the wall structure;

Figure 8 is a perspective view of a wall constructed without the use of concrete fill;

Figure 9 is a perspective view of one of the spacer blocks illustrated in Figure 8; and

Figure 10 is a fragmentary horizontal sectional view of the wall structure taken substantially along the line 10—10 of Figure 8.

Referring now to the drawings more in detail, wherein like numerals have been employed to designate similar parts throughout the various figures, it will be seen that for purposes of illustrating the invention, the same has been shown in its practical application to wall and floor sections. In the drawings the walls are designated

generally by the numerals 10 and 10a and the floor is designated generally by the numeral 12, Figure 1. Each of the walls 10 and 10a comprise two parallel wall sections, an inner section 14 and an outer section 16.

The inner wall section 14 comprises a plurality of wall slabs or plates 18, and the outer wall section 16 comprises similar wall slabs or plates 20. The wall slabs or plates 18 and 20 are maintained in spaced relationship by means of spacer members 22.

It will be noted that the wall slabs 18 and 20 are of identical construction, each having an intermediate longitudinal protuberance 24. These protuberances extend longitudinally and are disposed in pairs so that the protuberances on oppositely disposed plates 18-20 extend toward each other from the inner side of their respective plate. The upper and lower margin of the protuberances 24 provide undercut shoulders 26. These undercut shoulders 26 are designed to interlock with complimentary undercut shoulders 28 provided along oppositely disposed margins of each spacer member 22, Figure 5.

The undercut shoulders of the spacer members or blocks 22 are provided at opposite extremities or margins of protuberances 30. Upper and lower margins or extremities of each spacer member 22 presents spacer sections 32, which are adapted to be positioned between oppositely disposed protuberances 24 of the plates 18-20, as clearly illustrated in Figures 1, 4 and 6. The vertical length of the spacer sections 32 is substantially equal to one-half the width of the plate protuberances 24 thereby enabling the section 32 of one spacer member and the section 32 of the adjacent spacer member to cooperate in securing oppositely disposed plate protuberances 24 in spaced relationship.

Inner plate surfaces 34 extending from opposite margins of each plate protuberance 24 has a width which is substantially equal to one-half of the vertical length of the spacer protuberances 30 thus these spacer protuberances 30 are adapted to completely seal or interlock with the spaces bounded on one inside surfaces 34 of adjacent plates Figure 4 and on opposite sides by the protuberance shoulders 26. In this manner the protuberances 30 of each spacer member is capable of making a dovetail interlock with a pair of adjacent wall plates 18 or a pair of adjacent outer wall plates 20.

One of the important advantages afforded by the present invention resides in the fact that the wall plates and spacer members may be coupled or interlocked one upon the other in a very simple manner. In fact these parts may be placed one upon the other much in the same way conventional brick or blocks are laid one upon the other in the building of a wall. After a suitable foundation has been laid a plurality of spacer blocks or members constituting the upper half of the spacer members 22, just described, may be distributed along the upper surface of the foundation. See for example in Figure 4, where the plates 18 and 20 are interlocked with the upper half of spacing member 22. To associate the plates 18-20 with complementary spacing members 22 it is only necessary to lower the plates into position so as to interlock the lower shoulders 26 of the protuberances 24 with the upper shoulders 28 of the spacer member 22.

In instances where it is desirable, binding materials such as mortar or cement may be employed between the interlocking shoulders. How-

ever, this is not essential to the satisfactory use of the invention.

After the first or lower-most row of plates 18 and 20 have been positioned in interlocking relationship to the upper half of the section of a spacer member 22, companion spacer members may now be lowered into position. For example in Figure 4, after the lower-most wall plates 18-20 have been interlocked with the upper half 10 of the lower-most spacer members, these walls and their associated spacer members are in position to receive spacer members to interlock with the upper shoulders 26 of the wall protuberances 24. These spacer members may be conveniently lowered into position so as to bring the lower-most undercut shoulders 28 of the spacer members into interlocking association with the upper-most shoulder 26 of the oppositely disposed wall plates 18-20. After these spacer members have been placed in position as illustrated in Figure 4 so as to interlock the lower-most shoulders 26 of these plates with the upper-most shoulders 28 of the spacer members 22. This operation may be continued until the desired height of wall is obtained.

It will be apparent from the foregoing description that the spacer members may be spaced along the protuberances of the plates in any desired relationship. When it is required to provide a door opening or window in the wall, the wall plates 30 and spacer members may be omitted. The adjustable positioning of the spacer members facilitates the ease with which these openings may be provided. Likewise there is no limitation as to the length of the wall that may be erected and the spacer members may be set or positioned to accommodate any desired wall length. The spacer members are not limited to be used with wall plates of any given length but are adapted, because of their adjustable relationship with respect to the wall plates, to be used with various sizes. When desired concrete fill 36 may be introduced between the spacing members 22, as clearly illustrated in Figure 2. Concrete 36 cooperates with the spacer members 22 in binding the wall plates together.

The invention is by no means limited to the use of the described plates and spacer members in walls but contemplates the application of these parts to floors as well. In Figures 1, 3, 6 and 7 a floor is designated generally by the number 12. It will be seen that this floor comprises a plurality of adjacently positioned upper floor plates or slabs 18a and lower floor plates 20a.

The floor slabs 18a-20a are separated by spacer members 22, and each slab is provided with a projection 24 as previously described. The shoulders 26 of the slabs 18a-20a interlock with complimentary shoulders of the spacer members 22 in the manner previously described in connection with the wall slabs 18-20. Instead of positioning the plates vertically they are positioned horizontally. As shown in Figure 1, the floor plates 18a-20a adjacent to wall 10 are first coupled with the half section of the spacer member 22. Then the next spacer member is associated with these floor plates. Additional floor plates and spacer members are added by building toward the right, Figure 1. Spaces 38 are provided between adjacent plates which may be filled with concrete 36a as shown in Figure 3. The concrete 36a is poured between spacer members 22 from the top of the floor and it is important to note that concrete 36a and the concrete 36 previously described join as an integral mass at the junction of the wall and floor structures. This is clearly illus-

trated in Figure 6. In instances where it is desirable suitable reinforcing bars may be laid within the concrete.

Figures 6 and 7 illustrate the manner in which the floor and walls may be joined. Figure 7 illustrates the manner in which the concrete 36a joins with the concrete 36 in securing the two sections together. In Figures 6 and 7 the upper margin of one wall and the lower margin of the upper wall join with a section which has been designated generally by the numeral 40. This section 40 may extend completely around the floor and includes vertical wall slabs or plates 18-20 coupled together by upper and lower spacing members 22a. This construction may be eliminated in instances where it is not necessary to join a floor margin to upper and lower walls. It will be noted that the inner and outer slabs associated with the spacer members 22a are of a vertical width which is less than the plates or slabs previously described in that they must be the same in vertical width as the overall vertical dimension of the floor 12.

In Figures 8, 9 and 10 a wall designated generally by the numeral 10b is shown. This wall 10b is made up of inner and outer slabs or plates 18 and 20 respectively which are identical in construction with the wall slabs previously described. Particular attention is directed to spacing members 22b. These are substantially similar in structure to spacer members 22 previously described except that the spacing members 22b are greater in thickness. This increase in stock thickness precludes the necessity of employing fill between the spacer members. Identifying numerals have been employed for the structural details of the parts shown in Figures 8 to 10 inclusive which correspond with previously described details of Figures 1 to 7 inclusive.

It has been found practical to produce the plates and spacer members of the present invention of either concrete or lighter materials capable of being poured, such as a material known on the market at "Waylite" and other similar materials have proven satisfactory. It will be noted that in instances where required, recesses 42 may be provided in the spacer members 22 to accommodate pipe, conduits and the like. Other sizes and shapes of recesses may be provided to accommodate needs incident to the use of the slab and spacer structures. By having the protuberances 24 extending longitudinally and intermediate of the margins of the wall plates, considerable strength is contributed to the plates. In other words the protuberances 24 not only provide a simple and effective interlocking means but also a means for contributing considerable strength to the plates. It will be apparent from the foregoing description that a wall or floor may be constructed by the use of slabs and spacer members of the present invention with a minimum amount of effort and skill on the part of the builder. Also, the present invention eliminates the necessity of driving or inserting keys within longitudinal grooves and hence breakage of parts is reduced to an absolute minimum. That is to say, in using the plates, or spacer member or blocks, these parts are built one upon another

or one adjacent another without the necessity of forcing a key of one part longitudinally into a keyway or aperture of another part. Also, the parts described herein may be manufactured or preformed with the greatest economy and without the necessity of employing special machinery and equipment. Hence the present invention makes it possible to erect a building of sturdy construction with the greatest economy. Walls and floors constructed in accordance with the teachings of the present invention are not only exceptionally strong and rigid but provide insulated air spaces which materially contribute to their usefulness. Both the interior and exterior surfaces of the slabs permit of the application of coatings thereto. In some instances it may be advantageous to apply a thin brick veneer to the exterior surface or a coating of cement, merely for the purpose of ornamentation. Likewise the interior surface area makes it possible to receive a covering of cement, plaster, or the like.

While certain detail structural features have been disclosed and described herein, it will be obvious that the present invention is not limited to these structural details but is capable of other modifications and changes without departure from the spirit and scope of the appended claim.

The invention is hereby claimed as follows:

- 30 A building structure including two spaced and parallel sections each comprising a plurality of elongated plates with the longitudinal edges thereof juxtaposed, said plates having substantially centrally disposed elongated ribs disposed longitudinally thereof and extending inwardly toward and directly opposite the ribs of opposed plates, the ribs of each section being parallel and of uniform cross section, and each rib having undercut edges providing shoulders whereby to 35 form mating shouldered recesses between the juxtaposed edges of two adjacent plates in each section, and relatively narrow spacer members interposed in spaced pairs between opposed plates to form passages between opposed sections, 40 each spacer member having oppositely disposed and outwardly extending shouldered projections complementary with the mating recesses between the shouldered ribs of opposed pairs of plates and fitting therein to lock together adjacent plates 45 of opposed sections, said spacer members being shiftable laterally with the projections thereon 50 of opposed sections, said spacer members being slidably along mating recesses to selectively vary the passages between said spacer members.

OTTO S. JACOBSEN.
